CLAIM

The ornamental design for a produce preserver, as shown and described.

DESCRIPTION

FIG. 1 illustrates a top view of the claimed design for a produce preserver;

FIG. 2 illustrates a front view thereof;

FIG. 3 illustrates a left-side view thereof;

FIG. 4 illustrates a right-side view thereof;

FIG. 5 illustrates a rear view thereof;

FIG. 6 illustrates a bottom view thereof; and,

FIG. 7 illustrates a perspective view thereof.

The EvriFresh mark is part of the claimed design and is owned by Evriholder Products, Inc.
